(57) **CLAIM**

The ornamental design for a clothes rack as shown and described.

DESCRIPTION

1. Clothes rack

1.1 : Perspective

1.2 : Front perspective

1.3 : Right

FIG. 1 is a perspective view of a clothes rack showing our new design; FIG. 2 is a front perspective view thereof; FIG. 3 is a right side elevational view thereof, the left side elevational view being a mirror image; The broken line disclosure shown is understood to represent portions of the clothes rack in which the claimed design is embodied, but which form no part of the claimed design.
